NORMAN W. STORER, OF PITTSBURGH, PENNSYLVANIA, ASSIGNOR TO WESTINGHOUSE ELECTRIC AND MANUFACTURING COMPANY, A CORPORATION OF PENNSYLVANIA.

VOLTAGE-REGULATING SYSTEM.

1,226,142.

Specification of Letters Patent.

Patented May 15, 1917.

Application filed January 7, 1914. Serial No. 810,790.

To all whom it may concern:

Be it known that I, NORMAN W. STORER, a citizen of the United States, and a resident of Pittsburgh, in the county of Allegheny and State of Pennsylvania, have invented a new and useful Improvement in Voltage-Regulating Systems, of which the following is a specification.

My invention relates to voltage-regulating systems, and it has special reference to such systems as are adapted to maintain a substantially constant voltage upon a circuit which would otherwise be subject to wide fluctuations of voltage.

One of the objects of my invention is to provide a system of the above indicated class which shall be simple in arrangement and which shall operate effectively and quickly in accordance with variations in circuit conditions for maintaining substantially constant voltage upon translating devices, such, for instance, as the lamps which are commonly employed in electric railway cars.

Another object of my invention is to provide a regulating device of simple and inexpensive construction which shall respond quickly to predetermined changes of conditions of an electric circuit, and the movement of which may be instantly arrested under certain conditions, whereby the apparatus becomes "dead beat" and "overshooting" is precluded.

More specifically, one of the objects of my invention is to provide a voltage regulator for maintaining constant voltage upon the lighting system of an electric car having a control system like that shown and described in my co-pending application, Serial 781,742, filed July 29, 1913, and assigned to the Westinghouse Electric & Mfg. Company.

My invention may best be understood by reference to the accompanying drawing, the single figure of which is a diagrammatic view of a motor control-system embodying a voltage-regulating system and device constituting my invention.

Referring to the drawing, a plurality of motors 1 and 2 are supplied with energy from a supply circuit or trolley conductor 3 through a line switch 4, a starting resistor

5, resistor-controlling switches 5^a, an electro-responsive relay 6 and a storage battery or other energy-accumulating device 7 to 55 a return circuit G.

The portion of the system just recited is merely illustrative of any well-known type of motor control system, with the exception that the battery 7 is included in circuit therewith and is periodically charged and discharged under certain conditions of operation, as set forth fully in the herein-before mentioned co-pending application.

Under normal conditions, when the line 65 switch 4 is closed, a circuit is first completed through switch 4, resistor 5, motors 1 and 2, energizing coil of the relay 6 and an adjustable resistor 8 to the return circuit G. Immediately upon the supply of energy to 70 the motors, the relay 6 raises its movable contact member 9 into engagement with its stationary contact terminals 10, thereby completing a circuit from the negative side of the battery 7 through conductor 11, co-operating contact members 9 and 10 of the relay 6, and energizing coil of relay 12 to the positive side of the battery 7. The relay 12, being thus supplied with energy, is raised to complete a circuit from conductor 80 13 through its co-operating switch members 14 and 15 to the positive side of the battery 7. Thus, the motor current is caused to traverse and charge the battery 7.

The adjustable resistor 8, however, carries 85 a portion of the motor current, being connected in multiple to the battery 7, and the amount of current therein depends upon the resistance thereof, which is normally set to insure that the total charging current 90 of the battery in a predetermined period of time shall be just sufficient to maintain it in a fully charged condition, which, of course, will depend upon the character of the service to which the equipment is applied.

Also connected in multiple to the battery 7, are a plurality of translating devices 17 and 18, which may, for example, respectively, constitute the driving motor of a 100 compressor set, commonly employed upon railway cars, and the electro-magnets of the usual control systems for the driving motors. A plurality of lamps 19, constituting

the car-lighting system, are furthermore connected across the battery 7 in circuit with an energy-consuming device or variable resistor 20.

5 Under conditions of motor operation, the motor current is divided into several paths including devices 7, 17, 18 and 19, and is utilized for operating said devices. If the current is sufficient for that purpose, the battery 10 7 is charged. If, however, the motor current, due to the conditions of operation, is less than the required amount for operating this auxiliary apparatus, the battery 7 is forced to assist the motor current and discharge 15 some of its energy through the auxiliaries. Thus, the voltage of the circuit including lamps 19 is liable to fluctuations of a considerable range, and, in order to eliminate these fluctuations and maintain a constant voltage, the resistor 20 is adjusted in accordance 20 with the circuit conditions by means of apparatus and in the manner hereinafter set forth.

The resistor 20 is provided with a plurality of taps 21 which are severally provided with stationary contact terminals 22 for cooperative engagement with a movable conducting segment 23, the configuration of which is such as to engage or disengage said 25 terminals successively when moved in either direction. Mechanically associated with the conducting segment 23 is a double-ended piston 24 that is movably mounted within an operating cylinder 25 and is adapted to be 30 actuated by a suitable operating fluid in a well-known manner. Valves 26 and 27 are associated with the respective ends of the cylinder 25 and are adapted to govern the release and admission of operating fluid 35 thereto from a fluid reservoir 28.

In certain respects, the valves 26 and 27 are of like construction, in that they embody a plurality of chambers 31, 32 and 33, having intervening walls 34 and 35. The chambers 33 are open to the atmosphere through ports 36, the chambers 32 communicate with the operating cylinders, and the lower chambers 31 are in communication with the fluid-containing reservoir 28. The several walls 34 and 35 are provided with valve openings of the usual type, and a double-ended valve plug 37 is disposed within the chamber 32 of the valve 26 and is adapted to coöperate with the walls 34 and 35 for opening and 40 closing the openings therein. Normally, the valve plug 37 of the valve 26 is biased to its lowest position, in which case the communication between the fluid reservoir 28 and the operating cylinder 25 is closed, while the cylinder 25 is placed in communication with the atmosphere through the port 36.

The valve 27 differs from valve 26, in that it embodies a plurality of valve plugs 39 and 40 which are respectively located within 45 chambers 33 and 31 and are carried by a

stem 41. Normally, these valve plugs are maintained in their lowest position, thereby closing the operating cylinder 25 to the atmosphere and permitting the admission of operating fluid thereto.

70

The valves 26 and 27 are respectively provided with electro-magnets 42 and 43 for the purpose of actuating them and thus governing their operation.

The electromagnets 42 and 43 are, in turn, 75 governed by an electro-responsive device 44 comprising a pivotally mounted arm or contact member 45, one end of which is adapted to coöperate with a plurality of contact terminals 46, 47 and 48 in accordance with the 80 voltage conditions of the lighting circuit in which lamps 19 are connected. The other end of the pivotally mounted arm 45 carries a movable core 49 of an electro-magnet 50 having an energizing coil 50^a that is connected in multiple with the lamps 19 by means of conductors 51 and 52. Conductor 52^a connects contact arm 45 to the positive side of the battery 7, while conductor 53 connects the stationary contact terminal 46 to the energizing coil of electro-magnet 43, and conductor 54 connects contact terminal 47 to the energizing coil of the electro-magnet 42. Terminal 48 is isolated and has no electrical 85 connections.

95

The electro-magnet 50, which effects movements of the arm 45, is designed so that, under normal voltage conditions of the lighting circuit 19, it, in conjunction with an opposing spring 56, maintains the arm 45 in 100 contact with the terminal 47.

90

Assuming the various devices and circuit connections to be as shown in the drawing, if normal voltage obtains upon the lighting system, the arm 45 of the electro-responsive 105 device 44 is maintained in engagement with the contact terminal 47, in which case, the energizing coil of the electro-magnet 42 is energized, whereby the valve 26 is caused to admit operating fluid to the end 57 of the 110 cylinder 25. Inasmuch as the other end 58 of said cylinder is already subjected to the pressure of the operating fluid, no movement of said piston or of the conducting segment 23 is effected.

115

If, however, the voltage on the lighting system 19 rises to a predetermined amount, the electro-magnet 50 causes the conducting arm 45 to disengage the contact terminal 47 and to rest upon the terminal 48. As soon 120 as this disengagement is accomplished, the energizing coil of electro-magnet 42 is de-energized and the admission of operating fluid to the end 57 of the chamber 25 is cut off, while the operating fluid therein is permitted to escape to the atmosphere. Consequently, the pressures on the respective ends of the piston 24 are unbalanced and the piston is moved to the left, thereby moving 125 conducting segment 23 to the right and 130

progressively inserting sections of the resistance 20. Thus, the voltage of the lighting system 12 is immediately reduced.

As soon as the insertion of resistance has effected a reduction of voltage to the normal value, the spring 56 overcomes the electro-magnet 50 and returns the arm 45 into contact with the terminal 47. Thus, the electro-magnet 42 is again energized to close the release port and open the admission port of the valve 26, thereby establishing balanced pressures and holding the piston 24 and conducting segment 23 stationary.

On the other hand, if the lighting system voltage falls below the normal value for which the electro-responsive device 44 is adjusted, the spring 56 causes the arm 45 to engage contact terminal 46, thereby energizing the electro-magnet 43 of the valve 27 while maintaining the energization of the electro-magnet 42 of valve 26. The pressure in the end 58 of the cylinder 25 is thus released, and, inasmuch as pressure exists upon the opposite end of the piston 24, the latter is moved to the right, thereby moving conducting segment 23 to cut out sections of resistance 20 until normal voltage conditions are restored.

With the restoration of normal voltage conditions, the arm 45 is disengaged from terminal 46 and is moved to its middle position. By this action, the electro-magnet 43 is deenergized, and balanced pressures on the piston 24 are effected. Further adjustments of the resistor 20 are thus prevented until abnormal voltage conditions again obtain.

In this manner, the resistor 20 is gradually cut in and out in sections in accordance with the fluctuations of voltage across the battery 7, whereby the voltage on the lamps 19 is maintained constant. Moreover, the adjustments, of the resistor-controlling switch are quickly responsive to changes in circuit conditions, and the movements thereof are arrested instantly when normal conditions are restored.

Variations in the structure and arrangement and location of parts may be made without departing from the spirit and scope of my invention and such modifications are intended to be covered in the appended claims.

I claim as my invention:

1. In a voltage-regulating system, the combination with a supply circuit, translating means connected thereto, an energy-consuming device in circuit with said supply circuit, and a switching device for adjusting the circuit connections of said energy-consuming device, of power-operated means for actuating said switching device, a plurality of governing means associated with said actuating means, and means responsive to conditions of said supply circuit for caus-

ing the operation of both of said governing means to effect movements of said switching device in one direction, and for rendering one of said governing means inoperative to effect movements of said device in the opposite direction.

2. In a voltage-regulating system, the combination with a supply circuit, a resistance-governing switching device therein, and translating means connected to said circuit, of a power-operated device for actuating said switching device in opposite directions, a plurality of electro-magnetically controlled valves associated with said power device for governing its operation, and means responsive to electrical conditions of said supply circuit for normally energizing one of said valves, for deenergizing said valve for effecting movements of said switching device in one direction, and for energizing both of said valves for effecting movements thereof in the other direction.

3. In a voltage-regulating system, the combination with a supply circuit, a resistance-controlling switching device therein, and translating devices connected to said circuit, of a power actuated device for moving said switching device, a plurality of electro-magnetically controlled valves for governing the operation of said power device and electro-responsive means for energizing one of said valves under normal conditions of said supply circuit, for deenergizing said valve under other conditions of said circuit, and for energizing both of said valves under other conditions of said circuit.

4. In a voltage-regulating system, the combination with a supply circuit, translating means connected thereto, a resistance-governing switching device associated with said supply circuit, and a power-actuated device mechanically associated with said switching device for effecting movements thereof, of a plurality of electro-magnetically controlled valves for governing the operation of said power device, one of which is biased to its open position and the other to its closed position when their respective electro-magnets are deenergized, and means responsive to electrical conditions of said supply circuit for controlling the operation of said valves to effect variations of said resistance in accordance with predetermined circuit conditions.

5. The combination with a resistance-controlling switching device, and a fluid-operated mechanism associated therewith for moving said switching device, of a plurality of valves for governing the operation of said fluid-operated mechanism, one of said valves being biased to open position and the other to closed position, means for opening the valve that is biased to closed position under normal conditions of an electric circuit,

and means coöperating therewith for concurrently closing the other valve, under other predetermined conditions.

6. The combination with a supply circuit, 5 a resistance-controlling switching device connected thereto and an operating piston associated with said switching device and adapted for movements in opposite directions, of a source of operating fluid, a plurality of electro-magnetically controlled valves for governing the admission and release of operating fluid to the respective ends of said piston, and means responsive to voltage conditions of said supply circuit for controlling the supply of energy to either one or both of said electro-magnetically controlled valves, whereby said resistance is varied.
7. The combination with a supply circuit, 10 a resistance-controlling switching device connected therein, translating means con-

nected to said circuit, a fluid-actuated device for moving said switching device to cut in and out the resistance, a source of operating fluid, and a plurality of electro-magnetically controlled valves associated with opposite ends of said power device for controlling the admission and release of the operating fluid, one of said valves being initially open and the other closed, of means responsive to voltage conditions of said supply circuit for energizing said valves singly or concurrently for causing said resistance to be cut in or out.

In testimony whereof, I have hereunto 25 subscribed my name this 31st day of Dec. 1913.

NORMAN W. STORER.
